UNITED STATES PATENT OFFICE.

WARREN F. KAYNOR, OF WATERBURY, CONNECTICUT, ASSIGNOR TO WATERBURY
BUTTON COMPANY, OF WATERBURY, CONNECTICUT, A CORPORATION OF CON-
NECTICUT.

STREET-CAR TOKEN.

Application filed March 29, 1922. Serial No. 547,647.

To all whom it may concern:

Be it known that I, WARREN F. KAYNOR, a citizen of the United States, and a resident of Waterbury, county of New Haven, and 5 State of Connecticut, have invented certain new and useful Improvements in Street-Car Tokens, of which the following is a specification.

This invention relates to metal coins or 10 trade-checks adapted to be used as a substitute for money, and more particularly to an improved form of street-car token.

One object of the invention is to produce 15 a coin or check of the above nature which will be extremely difficult to counterfeit.

A further object is to provide a device of this nature which will be simple, cheap to manufacture, and very ornamental and durable in use.

20 With these and other objects in view, there have been illustrated on the accompanying drawing several forms in which the invention may be conveniently embodied in practice.

25 Fig. 1 represents a side view of the two original metal sheets from which the coin or check is to be formed.

Fig. 2 is a side view of the two sheets shown in Fig. 1, after they have been soldered together.

30 Fig. 3 is a side view of the composite soldered sheet showing its appearance while it is being reduced in thickness by means of a pair of pressure rolls.

35 Fig. 4 is a perspective view of one form of composite rolled sheet from which the coin or check may be stamped.

Fig. 5 is a perspective view of a slightly modified form of composite rolled sheet.

40 Fig. 6 is a perspective view of a street-car token stamped from the composite sheet shown in Fig. 4.

45 Fig. 7 is a perspective view of a street-car token stamped from the composite sheet shown in Fig. 5.

During recent years there has been a quite 50 general adoption by street-car companies of six-cent fares, seven-cent fares, and other fares requiring two or more pieces of money. In order to avoid this unnecessary handling of coins and to facilitate the collection of fares, metal checks or tokens have in many instances been sold by street-car companies as a convenient substitute for the money fare. Most of such checks and tokens, how-

ever, were quite easy to copy, and this has naturally led to wide-spread counterfeiting.

With the present invention, the above difficulty is practically eliminated. Thus a trade-check or token embodying the principles of the invention will be substantially proof against counterfeiting, as well as serviceable and ornamental.

Referring now to the drawings in which like reference numerals denote correspond-

60 ing parts throughout the several views, 10 represents a relatively thick metal strip to the surface of which a relatively thin strip of metal 11 is secured by the solder 12. The composite sheet consisting of the soldered

65 strips 10 and 11 is next passed through a pair of pressure rolls 13 and 14, as clearly shown in Fig. 3. By this operation the

70 metal of the composite sheet is reduced slightly in thickness and is made more compact. It is also hardened somewhat by the

75 working of the metal in the rolls. The thick metal strip 10, which is preferably made of copper, forms the base or body of the com-

80 pleted coin, while the thin surface strip serves as the surface coating. While the

85 thin strip 11 may be formed of a single metal, if desired, it is preferably composed of a plurality of contiguous sections of dif-

ferent metals, each strip being preferably 85 uniform in width. Any desired metals may be employed to form the individual sec-

90 tions of the strip, such as gold, silver, cop-

95 per, nickel, German silver, etc. In the ex-

100 ample illustrated in Fig. 4, the base strip 12 may be composed of copper and may have soldered thereto a surface strip consisting of

105 a pair of thin outer sections 15 and 16 of German silver, and a central copper section

110 17.

In the embodiment illustrated in Fig. 5, a slightly more complicated arrangement of surface strips is illustrated. In this figure,

115 a central gold strip 18 is surrounded in succession by a pair of German silver strips

19 and 20, a pair of copper strips 21 and 22, and a pair of edge strips 23 and 24 also

120 of German silver. The central strips 18—22 are preferably of equal width, while the

125 edge strips 23 and 24 are considerably wider than the central strips. After the composite

130 sheets have been rolled to size, the next

135 step is to stamp out the coins therefrom,

preferably by the use of a punch and die

140 of suitable dimensions. The completed coin

stamped out of the composite sheet illustrated in Fig. 4 is shown in Fig. 6. Similarly the completed coin stamped from the sheet illustrated in Fig. 5 is shown in Fig. 7.

5 While each surface strip illustrated on the drawing is of uniform width throughout its length, it will be understood that the invention also includes the use of surface strips of various lengths and whose sides 10 are neither parallel nor of uniform width.

While the trade-checks herein illustrated are shown provided with only single perforations in the shape of the letter C, it 15 will be understood that any other form and 15 number of perforations may be employed, as desired.

It will also be understood that the invention is not limited to the use of a striped metal layer on one side of the coin only, 20 but if desired both surfaces of the coin may be provided with such a striped layer.

The ratio of the thicknesses of the base and surface sheets may be varied through wide limits according to conditions. This 25 ratio, however, should preferably be about 40:1.

While there have been illustrated in this specification several forms in which the invention may be embodied, it is to be understood that these forms are shown for the 30 purpose of illustration only, and that the invention is not to be limited to the specific disclosures but may be modified and embodied in various other forms without 35 departing from its spirit. In short, the invention includes all the modifications and embodiments coming within the scope of the following claims.

Having thus fully described the invention, what is claimed is:

1. In a street-car token, a composite sheet comprising a relatively thick metal base, and a relatively thin surface layer soldered to said metal base, said surface layer comprising a plurality of adjacent sections of dissimilar metals, said sheet being hardened and reduced in thickness by subjection to pressure. 40

2. In a street-car token, a disk-shaped check having a relatively thick metal base, and a relatively thin surface layer secured to said base, said surface layer comprising a plurality of contiguous sections of dissimilar metals, said sections being of uniform width. 45

3. In a street-car token, the combination with a base, of a thin surface layer secured to said base, said surface layer being composed of a plurality of contiguous sections of dissimilar metals, whereby said token will 50 present an ornamental appearance and will be difficult to counterfeit. 55

4. In a trade-check, the combination with a metal base, of a surface layer comprising a plurality of thin strips of dissimilar 60 metals arranged side by side in the same plane, said trade-check being disk-shaped. 65

5. In a street-car token, the combination with a metal base, of an ornamental metal surface layer secured to said base, said ornamental surface layer being of parallel 70 strips of dissimilar metals whereby said token will be difficult to counterfeit. 75

In testimony whereof, I have affixed my signature to this specification.

WARREN F. KAYNOR.
